his ATTORNEY

UNITED STATES PATENT OFFICE.

PETER TRACZ, OF CARTERET, NEW JERSEY.

ALARM-LOCK.

1,323,729.

Specification of Letters Patent.

Patented Dec. 2, 1919.

Application filed November 2, 1918. Serial No. 260,772.

To all whom it may concern:

Be it known that I, PETER TRACZ, a subject of the Emperor of Austria, residing at Carteret, county of Middlesex, and State of New Jersey, have invented certain new and useful Improvements in Alarm-Locks, of which the following is a specification.

This invention relates to improvements in locks and particularly to types adapted for use on the doors of dwellings and like buildings.

The principal object of the invention is to provide a lock which will audibly announce that it has been operated.

Another object is to provide means, combined with the lock mechanism, which will indicate the particular door which has been unlocked.

These and other like objects are attained by the novel construction and combination of parts hereinafter described and shown in the accompanying drawings, forming a material part of this disclosure, and in which—

Figure 1 is a side elevational view showing a pair of doors indicating the application of the invention, the drawing being largely diagrammatic in character, and

Fig. 2 is a vertical sectional view taken through a lock made in accordance with the invention.

Referring to the drawings, common doors are indicated by the numerals 10 and 11, the same being set in jambs 12, arranged in the walls 14, of conventional type buildings.

Fixed in the edge frames of the doors are lock casings 14, the facings 15 of which are set flush with the door structure and held by screws passing through openings 16 in the usual manner.

Slidably engaged within the lock casing is a bolt 18, the same being guided at its inner end by projections 19, while the outer end of the bolt passes through an opening 20 formed in the lock face 15.

In the lower side of the lock bolt 18, is an angular opening 22, closely adjacent to the extending portion of the bolt, the same terminating in a recess or slot 23, and engageable within the opening 22 is the ward 24, of a key, its stem 25, passing into the lock in the usual manner.

It will be obvious that upon turning the keys, the ward 25 will make contact with the angular sides of the openings 22, moving the

lock bolt in accordance with the direction 55 which the key is turned.

Extending outward on the same side of the lock bolt is a projection 28, adapted to make contact with a lever arm 29, the same being pivoted on a pin 30, in the lock casing 60 and normally held against the projection, due to the pull of the tension spring 31, fixed to a pin 32 within the lock.

Movable with the lever 29 is another arm 33, carrying a metallic contact plate 35 upon 65 its other side, the same being adapted to form an electric circuit between the fixed contacts 36 and 37.

Engaged with the contacts 36 and 37 are lead wires 38 and 40, connecting with the 70 hinges 39 and 41, with which are engaged other wires 42 and 44, the former being in circuit with the battery 45, while the latter wire leads to an annunciator 46 arranged at any convenient location.

Also leading from the battery 45 is a wire 47, to the switch 48, where it may be placed in circuit with a wire 49, leading to a bell 50, from which extends the other circuit wire 51, to the annunciator, so that when 80 the switch is closed, and the key operated in the lock, contact will be made causing the bell to ring and the annunciator to show a number corresponding with the door.

Similarly, like wires lead from the lock 85 applied to the door 11, as 38' and 40', pass through the hinges 39' and 41' to the battery 45' and bell 50' to the same annunciator so that the operation of any door connected within the same circuit will be disclosed.

From the foregoing it will be readily observed that a key operated lock has been disclosed which upon being operated causes an audible signal to be given and coincidently therewith displays upon the annunciator the 95 particular door in which the keys have been used.

Having thus described my invention what I claim as new and desire to secure by Letters Patent, is—

In an alarm lock of the character described, the combination with a lock casing and a recessed, key-operated bolt slidable therein, projections within said casing for guiding the inner end of said bolt, of a projection 10 extending outwardly from said bolt within said casing on the side of the recess in the bolt, a pair of contacts mounted in said cas-

ing, a lever pivoted to swing in said casing, one of the arms of said lever being adapted to make contact with said projection, a spring for maintaining said contact normally, a plate carried by the other of said arms adapted to engage with said contacts for closing a signal and an annunciator circuit upon the operation of said bolt by a key,

substantially as described, and for the purpose set forth.

10

In testimony whereof I have affixed my signature.

PETER TRACZ.

Witness:

LOUIS ROSENBLUM.
